UNITED STATES PATENT OFFICE.

CHARLES HOFF, OF CINCINNATI, OHIO, ASSIGNOR OF ONE-HALF TO ANDREW JERGENS, OF SAME PLACE.

MACHINE FOR CUTTING PAPER PERCUSSION-CAPS.

SPECIFICATION forming part of Letters Patent No. 269,416, dated December 19, 1882.
Application filed March 19, 1882. (No model.)

To all whom it may concern:

Be it known that I, CHARLES HOFF, of Cincinnati, county of Hamilton, and State of Ohio, have invented certain new and useful Improvements in Machines for Cutting and Packing Toy Paper Caps, of which the following is a specification.

This invention relates to machines for cutting and automatically packing paper caps. Its object is to provide suitable means for cutting circular caps from a sheet dotted with rows of fulminate pellets without danger of exploding them, and to automatically deliver the caps into boxes for sale. These objects are accomplished by the means illustrated in the accompanying drawings, in which--

Figure 1 is a central vertical longitudinal section of my improved machine. Fig. 2 is a side-elevation of the same upon a diminished scale. Fig. 3 is a detail view, in front elevation, of the cutters, the plunger carrying the same, and plunger guiding and driving devices. Fig. 4 is an elevation of one of the cap-cutters, and the gravitating follower which slides within it, drawn to about the full size. Fig. 5 is a perspective view of the machine.

Similar reference-letters indicate like parts wherever they occur in the different views.

The bed-plate A, suitably mounted upon a supporting-frame and longitudinally grooved to receive and guide the open sliding sheet-carrying frame B, with the devices for clamping the sheet upon said frame and automatically feeding the same to the cutting mechanism, as well as the vertically-sliding plunger C, and the head-stock or standards D, in which it slides, are substantially the same as shown and described in Letters Patent No. 245,826, dated August 16, 1881.

40 I will now describe the newly-invented means by which I am enabled to cut and pack circular caps and greatly increase the capacity and efficiency of my said former machine.

Projecting from the front of the plunger C is a bar, E, in which are rigidly secured the cylindrical cutters F. These cutters are serrated around the lower edge, forming sharp spear-like points for piercing through paper, which is thus, after the points have punctured it, severed by a drawing cut, the edges of the teeth being sharpened their full length. With-

in each cutter is a sliding rod or tube G, which is provided with a head or projecting flange around the top to limit its downward movement. There is also suspended from the bar E a perforated presser-plate, H. The rods by which it is suspended pass loosely through perforations in bar E. The heads of the rods resting upon the upper side of the plate E lift the plate H a short distance above a similarly perforated stationary plate, I, secured over the transverse opening in the bed-plate A when the plunger has reached the upper limit of its stroke. During the time the presser-plate is lifted above the stationary plate I the cap proper is fed forward by a ratchet actuated by the plunger and acting upon rack-teeth in the sliding sheet-carrying frame B. The perforations in plates H and I are of a size and in position to permit the free passage of the tubular cutters. When the plunger is brought down spiral springs K, coiled around the presser-rods and compressed between the presser H and bar E, hold the paper clamped between the plates H and I until the cutters and followers G have been withdrawn from the plates by the upward movement of the plunger C.

The followers G, if made of tubes, should be heavy enough to rest firmly upon the paper without tearing it unevenly when the caps are nearly severed. I prefer to make these followers of metal rods bored up from the bottom to let them press evenly around the edge of the cap-piece without touching the fulminate pellet.

Above the plate E, upon plunger C, is secured a light metal plate, g, to press upon the heads of the followers G after the cutters have severed the caps and forced them through the stationary plate, to discharge the caps into the tubes J, in case any of the followers should stick by small pieces of paper turning up against their edges, and also to keep them from jumping out during the rapid motion of the plunger C. This plate g has perforations above the rods which suspend the presser-plate to admit of the free passage of the rods on the downward stroke of the plunger.

The discharge-tubes J are arranged immediately under the perforations in plate I. I have shown the tubes large enough at the top to inclose four of the openings in plate I. At the bottom they taper to the size of the

box *j*, into which the caps are to be packed, so that four caps are discharged into each box at each stroke of the plunger *C*.

Underneath the bed-plate *A* in the frame of the machine is a frame, *K*, made of light angle-iron. This is secured to the legs and cross-pieces of the frame. This is the guide for the sliding bed-plate *L*. Upon one edge of this bed-plate is a rack, *l*, the teeth of which are engaged by a detent, *M*. When the detent is disengaged from the rack the bed-plate is drawn forward by a weight, *v*, at the rear of the machine, through a cord, *v*², which is attached to the front of the bed-plate, thence passing around a sheave secured in front of the frame *K*, underneath the frame and up at the rear, over a sheave in a standard at the rear of the machine. The detent *M* is connected to a bell-crank, *m*, which is fulcrumed upon a standard secured in bed-plate *A* by a rod, *M'*. The lower arm of the bell-crank is armed with a pin, which projects over the sliding sheet-carrying frame *B*, to engage with pins *b*, projecting up from said frame. One of these pins striking the pin in the lower arm of the bell-crank disengages the detent *M* momentarily from the rack *l* and permits weight *v* to draw the bed-plate *L* forward one tooth, when the detent, dropping again, stops it with a row of empty boxes under the tubes *J*. The distance the pins *b* are placed apart determines the number of caps that will be packed in each box. The cap-boxes I prefer to place in trays (not shown) partitioned off to hold quite a number of boxes. These can be filled by the attendants and placed properly by suitable registering-pins upon the bed-plate *L*, and removed when filled, to be replaced by empty ones, so that little time is lost in the operation of the machine, one machine keeping several attendants busy.

Instead of the gage used on my former machine for registering the sheets properly on frame *B*, I use registering-pins *b*², which project up from frame *B*, and upon my machine for printing the sheet with the fulminate dots I have pins similarly arranged. Now, by perforating a pile of cap-paper with holes to register with these pins, I save all trouble of gaging.

In the drawings I have shown in the different views my machine provided with one and two rows of cutters; but it is evident that any number of them may be arranged to cut at each stroke, as the cutters sever the paper without drawing it out of the position in which it is placed upon the frame, while the hollow plungers *G* protect the pellets. The danger of explosion is thus wholly avoided.

The plunger *C* is actuated by a crank-shaft, *N*, journaled in boxes secured in the headstock. This shaft is driven by hand, as shown, but may be driven, if desired, by a band over the wheel *O*. I use I counterpoise the weight of the plunger *C* by a spiral spring attached to the upper end of its pitman and to the upper timbers of the room or building.

On my improved machine I am enabled to perforate through several sheets at the same time, thus greatly increasing the capacity of the machine.

If the devices for automatically feeding the cap-boxes are dispensed with, then an alarm should be connected by a wire to the bell-crank *m*, to sound a signal when the requisite number of caps are packed into the row of boxes.

The cylindrical cutters *F* will cut out and discharge caps perfectly without the followers *G*, and when the larger, or what are known as "bomb," caps are made, the plungers *G* may, without inconvenience, be dispensed with, as the weight of the fulminate pellets will carry the caps into the boxes; but in cutting the light common caps the followers insure their discharge through the tubes into the boxes.

It is evident that instead of the tubular cutters striking through the perforations of the stripper *H* and being encircled thereby when in the act of cutting the sheet or being withdrawn therefrom said cutters might be encircled by tubular stripper-sleeves, said sleeves being connected to the followers *G* by pins passing through vertical slots in the cutters.

What I claim as new, and desire to secure by Letters Patent, is—

1. The combination, substantially as hereinbefore set forth, of the spear-pointed cylindrical cutters *F* and plunger *C* with the perforated stationary plate *I* and similarly-perforated presser-plate *H*.

2. The spear-pointed cylindrical cutters *F*, in combination with a perforated plate, as *I*, and the strippers arranged to encircle the cutters and press yieldingly upon the cap-sheet to retain it in place while it is being severed into caps.

3. The combination, substantially as specified, of the grooved bed-plate *A*, open sheet-carrying frame *B*, and stationary perforated plate *I* for the cutters to strike through, with the spear-pointed cylindrical cutters *F*, plunger *C*, and its driving mechanism, and the strippers arranged to press yieldingly upon the cap-sheet to retain it upon the perforated plate while the cutters are withdrawn.

4. The combination, substantially as hereinbefore set forth, of the grooved bed-plate *A*, open sheet-carrying frame *B*, adapted to slide within said bed-plate, with the plunger *C*, shaft *N* and its connecting-rod or pitman, the spear-pointed cylindrical cutters *F*, and discharge-tubes *J*.

5. The combination, substantially as specified, of the grooved bed-plate *A*, the open sheet-carrying frame *B*, adapted to slide in said bed-plate, and pins *b*, projecting up from said frame *B*, with the bed-plate *L*, rack *l*, detent *M*, bell-crank *m*, connecting-rod *M'*, rope *v*, and weight *v*, the parts being arranged to automatically feed the bed-plate *L* and its boxes forward when the detent is released from the teeth of rack *l*.

6. The combination, in a cap-cutting machine, of the cap-sheet-feeding devices con-

sisting of grooved bed-plate A, sliding frame B, registering pins b², and devices for clamping the sheet on the frame, the cap-severing mechanism consisting of the tubular spear-pointed cutters F, follower G, plates H and I, and plunger C, and the box-feeding devices consisting of frame K, sliding bed-plate L, de-

tent M, rod M', bell-crank m, rack l, cord r, and weight l', as specified.

CHARLES HOFF.
